UNITED STATES PATENT OFFICE

LLOYD J. BOBB, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA

ELECTRODYNAMIC SOUND REPRODUCING SYSTEM

Application filed January 22, 1930. Serial No. 422,638.

The present invention relates to sound reproducing systems and particularly refers to systems employing sound reproducing devices known in the art as electrodynamic reproducers which have a movable coil armature adapted to vibrate in accordance with signal currents flowing therein and a fixed field coil adapted to be energized from an external source.

10 The principal object of the invention is to provide means for energizing the fixed field coil of the sound reproducer from a source of pulsating uni-directional current such as rectified alternating current of 60 cycles and 110 volts, although other frequencies and voltages may be used without materially affecting the operation; or from any other source of pulsating uni-directional current such as a dynamo-electric machine 15 which may generate a uni-directional current having a commutator ripple.

Another object is to provide means for substantially reducing the hum effects which are generally present in rectified alternating 20 current supply systems and which cause annoying disturbances in the sound reproducer or loud speaker.

A further object is to provide energization of the fixed field coil of the sound reproducer from the filter system of a rectified alternating current supply as is generally used for energizing vacuum tubes of a radio 25 signaling system.

Other objects and advantages of the invention will appear more fully hereinafter from the following detailed description taken together with the accompanying drawings, in which:

Fig. 1 is a schematic diagram of an electrodynamic sound reproducer connected in accordance with my invention;

Fig. 2 is a further modification showing the sound reproducer energized from the filter system of a power supply of a vacuum tube 30 signaling system.

Referring to Fig. 1 of the drawings, the sound reproducer comprises the usual fixed field coil L₁, the movable armature coil L₂ associated therewith and the vibrating diaphragm LS, which may be a cone or any

other acoustic diaphragm and which may be attached to the vibrating coil L₂ in any suitable manner. The field coil L₁ is energized from an alternating current source through a suitable transformer T₁ through the rectifier D which may be a half-wave or a full-wave rectifier of any suitable type such as an electrolytic rectifier, a metallic rectifier of the dry type or a thermionic tube rectifier. The armature coil L₂ is adapted to be energized by signaling currents from the transformer T₂ which may be, in the present instance, the output transformer of the last stage of amplification of a receiving system which may be of the push-pull type. The signal currents flowing through the coil L₂ react on the field produced by the coil L₁ and cause the armature coil L₂ to vibrate in accordance with the signal currents, thereby vibrating the diaphragm LS to generate sound. The current flowing through the field coil L₁ fluctuates more or less due to the inherent action of the rectifier D thereby producing a fluctuating field which affects the vibrating coil L₂ and these fluctuations are reproduced in the diaphragm LS in the form of a steady audible hum which is annoying and undesirable in sound reproduction. To eliminate this undesirable hum or to at least reduce it to a substantial minimum, a resistance R is provided in shunt with the field coil L₁ to introduce a desired portion of the fluctuating current into the armature coil L₂ in opposition to the fluctuations produced therein by the action of the fluctuating field. The fluctuations introduced into the coil L₂ by means of the resistance R and those which are present in the coil L₂ due to the action of the fluctuating field being of the same general character but arranged in opposite phase by means of the resistance R, they substantially neutralize each other, thereby eliminating undesirable hum in the sound reproducer LS. The amount of the fluctuating current desired to be introduced into the coil L₂ may be determined by means of the variable tap P which may be permanently set after the desired adjustment is found.

In Fig. 2 is shown an arrangement in which the field coil L₁ of the sound reproducer is

used additionally as a choke coil of a filter system of the general type which includes the condensers C_1 and C_2 connected across the output of a thermionic tube rectifier D , the 5 plates of which are energized from the secondary S_2 and the filament from the secondary S_1 of the transformer T_1 which is connected to an alternating current supply by means of the primary P_1 . The output of the 10 rectifier is connected through the filter to a load indicated at Z which may be the plate circuits of a cascaded series of vacuum tubes of a radio signaling system. As shown in Figs. 1 and 2, the armature coil L_2 is energized with signaling currents from the transformer T_2 and the opposing fluctuations are introduced into the armature coil L_2 by means of the resistance R connected in shunt with the field coil L_1 and the amount of the fluctuating current may be varied by the variable tap P as before. The function of the circuit of Fig. 3 is similar to that of Fig. 1 except that the field coil L_1 performs an additional function of a filter choke, thereby eliminating 20 the use of a separate choke coil. It is obvious that the opposing fluctuations may be introduced into the armature coil L_2 by other means than the resistance R .

All of the modifications described may, of course, be used to function in a manner reverse to that described, that is, instead of being used for sound reproduction, they may be used as a sound pick-up and the diaphragm LS may be replaced by a microphone 35 diaphragm, in which case, sound vibrations cause the movable coil L_2 to vibrate and generate sound representing currents which may be passed to an amplifier or other device through transformer T_2 .

40 While I have shown several embodiments of my invention for the purposes of illustration and description, other changes and modifications may be apparent to those skilled in the art without departing from the scope 45 of the invention and I, therefore, desire to be limited only by the scope of the appended claims.

I claim:

- 50 1. In a device for translating electrical signal energy into sound energy having a fixed coil, a movable coil associated with said fixed coil and adapted to be vibrated in the field of said fixed coil, means for energizing said fixed coil from a source of pulsating uni-directional current whereby undesirable fluctuations are produced in said movable coil, means for energizing said movable coil from a source of signal currents whereby said movable coil is caused to vibrate in accordance with said signal currents, and means connected in shunt with said fixed coil for introducing fluctuations into said movable coil which are substantially equal and opposite in phase to the undesirable fluctuations produced in said movable coil by said fixed coil

whereby said undesirable fluctuations are substantially neutralized and their effects on said device largely eliminated.

2. In a device for translating electrical signal energy into sound energy having a fixed coil, a movable coil associated with said fixed coil and adapted to be vibrated in the field of said fixed coil, means for energizing said fixed coil from a source of pulsating uni-directional current whereby undesirable fluctuations are produced in said movable coil, means for actuating said movable coil from a source of signal currents whereby said movable coil is caused to vibrate in accordance with said signal currents, and means connected in parallel with said fixed coil and having at least a portion thereof connected in series with said movable coil for introducing fluctuations into said movable coil which are substantially equal and opposite to the undesirable fluctuations produced in said movable coil by said fixed coil whereby said undesirable fluctuations are substantially neutralized and their effects on said device largely eliminated.

3. In a device for translating signal energy into sound energy, the combination of a source of alternating current, a rectifier for converting said alternating current into uni-directional current having a ripple component, a coil connected between the electrodes of said rectifier whereby a strong magnetic field of constant polarity is developed around said coil, a conductive element mounted for vibrational movement within said field, means for passing signal currents through said conductive element, whereby said conductive element is vibrated at the signal current frequency, and means connected in parallel with said coil for diverting and introducing a regulable portion of said ripple component of said uni-directional current from said coil into said conductive element of a phase to substantially eliminate vibration of said conductive member by the variation in field intensity caused by the ripple component of said uni-directional current.
